FIG. 2

*Inventor
A. Weissenbach
By Wm. O. Reh
Atty.*

UNITED STATES PATENT OFFICE.

ALFRED WEISSENBACH, OF CHICAGO, ILLINOIS.

DESIGN FOR A CHILD'S DRESS.

6,041.

Specification for Design. Patented Nov. 16, 1920.

Application filed April 26, 1920. Serial No. 376,857. Term of patent 7 years.

To all whom it may concern:

Be it known that I, ALFRED WEISSENBACH, a citizen of the United States, residing at Chicago, in the county of Cook and State of Illinois, have invented a new, original, and ornamental Design for a Child's Dress, of which the following is a specification, reference being had to the accompanying drawings, forming a part thereof, in which—Figure 1 is a front elevation and Fig. 2 is a rear elevation, of a child's dress showing my new design.

I claim:

The ornamental design for a child's dress as shown.

ALFRED WEISSENBACH.
